UNITED STATES PATENT OFFICE.

JOSEPH GENTILE, OF BROOKLYN, NEW YORK.

HOSE CLAMP.

1,416,012.

Specification of Letters Patent. Patented May 16, 1922.

Application filed November 4, 1921. Serial No. 512,943.

To all whom it may concern:

Be it known that I, JOSEPH GENTILE, a subject of the King of Italy, and a resident of the borough of Brooklyn, in the county of Kings and State of New York, have invented certain new and useful Improvements in Hose Clamps, of which the following is a specification.

This invention has as one of its objects 10 to produce a hose clamp for re-enforcing pliable hose made of textile fabric, whereby they are effectively stiffened, supported and protected from bursting or injury from the outside.

Another purpose is to provide means, integrally combined with the clamp, for securing branch connections to the hose, holding the same in proximate engagement and protecting the joints.

A further object is to provide such devices in a plurality of forms, suited to varying conditions and circumstances, each 20 type being self-conforming, capable of tight adjustment after assembling, and of ready 25 application at any desired time.

These and other analogous objects are attained by the novel constructions, combinations and arrangement of parts herein-after described and shown in the accompanying 30 drawings, forming a component part of the disclosure, and in which:—

Figure 1 is a side elevational view of an internal explosion motor of conventional 35 type, together with its water cooling radiator, showing applications of the invention.

Figure 2 is a side view of one type of hose clamp as assembled ready for use.

Figure 3 is a plan view of the stamped 40 blank before bending.

Figure 4 is a side view showing a slightly modified clamp.

Figure 5 is a plan view of its blank prior to forming.

Figure 6 is a side view showing a further modification of the clamp.

Figure 7 is a like view of another modification including a lateral connection.

Figure 8 is a similar view showing an 50 elongated form of clamp having opposite side connecting elements.

Figure 9 is an end view of the same drawn to an enlarged scale.

Figure 10 is a plan view of the blank 55 from which it is made.

Figure 11 is a side view of a double or elongated type of inner element.

Figure 12 is a similar view of a single inner element.

Figure 13 is a transverse sectional view 60 taken on line 13—13 of Figure 9.

Figure 14 is a side elevational view of an elongated clamp formed with its supports and a plurality of engaging means.

This invention embodies improvements 65 over my invention for clamp described, illustrated and claimed in an application filed April 22nd, 1921. Serial #463,518.

In the drawings the numeral 20 designates in general a conventional type of explosion motor, together with its radiator 21, the same being engaged by a pipe or hose 22 from which the heated water returns to the radiator and a circulating pipe or hose 23 for carrying the water back to the motor 75 after being cooled by passing through the radiator.

A small hose 24 leads from the pipe or hose 23 to a thermostat 25 connected with the radiator, as shown in Figure 1, these 80 parts being of common use and form no part of the invention, they being illustrated merely to indicate uses of the hose clamps.

Disposed on the hose 23 is a type of clamp shown in detail in Figure 8 and on the hose 85 22 is a simple form of clamp, such as is shown in Figures 2, 4, or 6.

Stated generally, all of the several types of clamp are composed of two main elements, respectively inner and outer, and the 90 bolts by which they are constrained together upon the hose requiring them.

Referring now more specifically to Figures 3 and 5, showing the blanks for the outer members, they will be seen to consist 95 of essentially rectangular flat plates 30 having symmetrical recesses 31 in the central portions of their ends, the remaining tabs or ends 32 and 33 containing perforations 34 and 35, the former of which are elongated 100 for a purpose further on apparent.

Also in these plates, between the recesses 31 are figural openings 36 thereby reducing the weight, and improving the appearance of the clamps.

The metal disposed midway between the lateral edges and ends of the openings 36 is pressed to produce cavities of uniform depths, and as shown in Figure 3, may extend from one tab to another unbrokenly, 110

as at 37, or be divided into two sections, as at 38, in Figure 5. Attention is called to the extensions 39 and perforations 40 of the tabs 33 which will be referred to further on.

5 Finally the central portion of the plates, lying between the tabs, are bent cylindrically and the top portions are extended in parallel outwardly and the perforations 34 and 35 brought into register to receive clamp bolts 41 fitted with wing nuts 42 and the bodies of the bolts may be provided with lugs entering the elongated perforations 34 to prevent them from turning when manipulating the nuts in adjusting the clamps, 10 the finished forms of which are clearly evident in Figures 2 and 4.

The inner elements of the clamps are shown in Figures 11 and 12, the latter being used in connection with the outer elements

20 just described, the same consisting of a rectangular blank bent cylindrically into a tube 43 open at its upper adjacent end 44 and sheared as at 45 to produce tabs 46 containing perforations 47, the ends of the tabs 25 being turned reentrantly outward as at 48 and an indentation 49, constituting a detent made in the lip thus formed.

These blanks are suited to enter the cavities 37 or 38 and the tabs extended to be received between the tabs 34 and 35, the 30 bolts passing through the perforation 47.

The longer inner element, shown in Figure 11, is used in connection with the outer elements seen in Figures 6 and 7, the former 35 of which is distinguished merely by having its expanded portion extended over the entire area between its marginal edges which fit the hose, while the form shown in Figure 7 is plainly cylindrical from end to end as 40 at 51.

As will be seen, the tabs 46 of the inner elements are received between the tabs 33 and 34 of the outer element and are in a manner positioned by the extensions 39, 45 which also act as guards for the elements 48, the detents 49 of which engage in the perforations 40.

Again referring to Figure 7, it will be noted that an extension 52 reaches from the 50 center of the blank, which before bending is obviously shaped like a reversed T, the laterally extending arms of which are formed into an open ring 53 having outstanding clamp element 54 connected by a 55 bolt as shown, for the purpose of engaging a branch to the main hose.

The general arrangement of clamps for this purpose is shown in Figures 8, 9 and 10, the latter being a view of the flat blank 60 similar to but longer than those previously described and containing duplicate parts.

In addition the arm 52' extending from the central recess 31' at one edge, is formed with a strip 55 to be bent into a ring, as in 65 Figures 8 and 9.

Also sheared on the lines 56, at the center of the plate are T shaped elements 57 and 57' bent to form rings as shown in these last named figures and clamped at their ends, this type of clamp being known as a cross, 70 its application being seen in Figure 1.

A similar type of clamp may be provided without the sheared elements 57 and 57' having instead thereof a top central opening similar to that indicated in Figure 7. 75

In order to support as well as re-enforce a flexible hose or the like, the adaptation shown in Figure 14 may be used, the same consisting of an elongated guard or clamp 60 composed of a plurality of elements 30 80 integrally connected, having cut out 36 and tabs clamped as described.

The recesses are suited to receive the shorter inner clamp element 43 and extending rearward or above these outer clamp 85 elements are other, but smaller cylindrical elements 61 adapted to engage a rod, tube or similar support 62 arranged parallel and contiguous to the hose 63 to which the clamp 90 is engaged.

While certain preferred embodiments of this device have been shown and described, it will be understood that changes in form and details thereof may be made without departing from the scope of the invention 95 as defined in the appended claims.

Having thus described my invention, what I claim as new and desire to secure by Letters Patent, is:

1. A hose clamp comprising substantially 100 cylindrical inner and outer members, tabs on the outer member extending from its adjacent edges, tabs integrally formed from the bodies of said inner members opposite their adjacent edges, said inner tabs extending co-incidently between said outer tabs, co-operative detent elements engaging between said inner and outer tabs, and bolts for drawing each group of tabs together whereby the inner and outer elements of said 105 cylindrical members are contracted in diameter.

2. A hose clamp comprising an outer cylindrical member formed to present recesses in its interior, tabs extending from its spaced 115 longitudinal edges, one or more inner cylindrical members having spaced edges disposed oppositely to that of the outer member, tabs integrally formed with said inner members extending outwardly between the 120 tabs of the outer member, all of said tabs having registering openings, bolts passing through the openings, and means preventing said bolts from turning while being tightened.

3. A hose clamp comprising an outer cylindrical member formed to present recesses in its interior, tabs extending from its spaced longitudinal edges, one or more inner cylindrical members having spaced edges disposed 125 130

oppositely to that of the outer member, tabs integrally formed with said inner members extending outwardly between the tabs of the outer member, all of said tabs having registering openings, bolts passing through the openings, and detents for holding the openings in said tabs in alignment prior to inserting said bolts.

4. A hose clamp comprising inner and outer cylindrical members having opposed open longitudinal edges adapted to spring apart to pass over a hose, said inner members engaging in recesses in said outer members, registering tabs integral with said members, elements formed with the tabs of said inner members interengaging the tabs of said outer elements, and means for constraining each group of tabs whereby the interior diameter of the cylindrical members may be reduced.

5. A hose clamp comprising inner and outer cylindrical members having opposed open longitudinal edges adapted to spring apart to pass over a hose, said inner members engaging in recesses in said outer members, registering tabs integral with said members, elements formed with the tabs of

said inner members interengaging the tabs of said outer elements, means for constraining each group of tabs whereby the interior 30 diameter of the cylindrical members may be reduced, and means for supporting said clamp formed integrally with said outer member.

6. A hose clamp comprising an outer cylindrical casing suited to a hose and containing internal recesses, inner members suited to the recesses, means for clamping said casing and inner members upon a hose, and a support ring formed with said casing 40 disposed at an angle centrally thereof.

7. A hose clamp comprising an outer cylindrical casing suited to a hose and containing internal recesses, inner members suited to the recesses, means for clamping 45 said casing and inner members upon a hose, and branches extending in the manner of a cross from said casing, the outer elements of said branches being integral with said casing.

Signed at Brooklyn in the county of Kings and State of New York this 26 day of September A. D. 1921.

JOSEPH GENTILE.
